Chamberlain & Neumann ATTORNEYS.

UNITED STATES PATENT OFFICE.

MICHAEL HAWIE, OF BRIDGEPORT, CONNECTICUT.

BUSTLESS BUCKLE.

Application filed July 15, 1922. Serial No. 575,314.

To all whom it may concern:

Be it known that MICHAEL HAWIE, citizen of the United States, and resident of Bridgeport, in the county of Fairfield and 5 State of Connecticut, has invented certain new and useful Improvements in Rustless Buckles, of which the following is a specification.

The present invention relates to improvements in buckles, and more particularly to 10 the type of buckles known as "rustless back" buckles.

An object of the invention is to provide a buckle of this character, which may be 15 simply and economically constructed of two pieces of sheet metal, stamped to shape, and in which a comparative saving of both the metal going into the buckle, and the web secured to and co-operating therewith, may 20 be effected. A further object is to allow the secure fastening of the web, without stitching, or the use of other fastening means, other than that incorporated in the two parts of the buckle.

25 Still further objects consist in effectually securing the web to the buckle, so that it will withstand excessive strains, and in which the web will not readily become worn or chafed.

30 With the above and other objects in view, an embodiment of the invention is shown in the accompanying drawings, and this embodiment will be hereinafter more fully described with reference thereto, and the invention will be finally pointed out in the 35 claims.

In the drawings:

Fig. 1 is a perspective view of a buckle, embodying the invention, showing the clamping lever opened, and the two parts assembled and before attachment to the web;

40 Fig. 2 is a similar view, showing the web attached and unfolded;

45 Fig. 3 is another similar view, showing the web folded down upon itself;

Fig. 4 is a vertical sectional view, and showing the web looped through a cast-off, and carried beneath the closed clamping lever; and

50 Fig. 5 is a perspective view, showing the inner side of the buckle, and with the web attached.

55 Similar reference characters indicate corresponding parts throughout the several figures of the drawings.

Referring to the drawings, the buckle

comprises two stamped sheet metal parts, i. e., a body or frame member and a clamping lever member, the latter consisting of an operating arm 10, and a clamping arm 11, having a series of teeth 12 along its edge. The clamping arm is arranged at an approximate acute angle to the operating arm, and is provided with pintles 13 and 14, extending from opposite ends of the lever, and situated substantially contiguous to the junction between the operating and clamping arms.

The frame 15 is in the form of a bar having parallel upper and lower edges 16 and 17, and is provided at its ends with ears 18 and 19, bent at right angles and perforated as at 20 and 21 to receive and pivotally support the pintles 13 and 14 of the clamping lever.

A series of spaced V-shaped teeth 22, having their points directed toward the upper edge 16, and forming corresponding shaped openings 23 in the bar are struck from frame, and are bent outwardly and upwardly, the points being spaced away from the surface of the bar, before attachment of the web, as clearly shown in Fig. 1. The openings 23 are in line with the teeth 12 of the clamping arm, for a purpose which will be presently more fully pointed out.

The pivotal points of the clamping lever are arranged above the teeth 22 and openings 23, and the teeth 12 are given a circular movement toward the openings 23 with each operation of the lever.

The web 24 is engaged with the buckle by inserting its end 25 beneath the teeth 22, which are thereupon swedged, in a suitable manner, inwardly at their points toward the openings 23, to securely grip the end of the web, which is exposed at the inner side of the frame, at its portions engaged in the openings 23. The web is then folded downwardly, so that the points of the teeth 22 are directed into the bight of the fold, to thereby more securely grip the web, under excessive strains. It is then passed through the cast-off 26, and the upper reach 27 is inserted through the buckle, between the frame and the clamping lever, the latter being then closed, so that its toothed edge 12 engages the web, and presses it firmly against the inner face of the frame; the portions directly engaged by the points of the teeth 12, being tightly and frictionally engaged with the portions of the end of the web exposed

through the openings 23, to thereby firmly retain the upper reach in adjusted relation.

The inner side of the structure, as is clear from Fig. 4, is entirely free of any exposed metal parts, and is thereby rendered rust-proof. The buckle is quickly attachable to the web, is efficient in operation, and will not permit slippage or detachment of the web under the most severe strains, the teeth 10 12 so engaging the web as to directly resist any undue strains thereon, and more firmly grip the same proportionately to such strains.

I have illustrated and described a preferred and satisfactory embodiment of the invention, but it is obvious that changes may be made therein, within the spirit and scope thereof, as defined in the appended claims.

I claim:

- 20 1. A buckle comprising a sheet metal frame member and a lever member, said frame member including a back having forwardly projecting ears and a series of spaced apart inverted V-shaped cuts forming teeth, all of said teeth being struck outwardly from the back in a direction opposed to the direction of said ears, whereby the inner surface of said back between said ears is free of projections, the points of said 25 teeth extending substantially in the same direction upwardly as the apices of the cuts and being spaced from the outer surface of the back to permit the insertion of a web having its edge inserted downwardly between the teeth and the outer surface of the back and abutted by the base of the teeth, the end portion of the web being grippingly 30 engaged by said teeth, and having portions exposed through the openings formed by 35 the teeth at the inner side of the back, the 40

the web adapted to be folded downwardly upon the teeth to conceal them, the points thereof engaging the bight of the fold to increasingly grip the web upon downward pull thereon, the lever member being pivoted in the ears of the frame member and including an operating arm and a clamping arm arranged at an angle thereto and having a gripping edge adapted in the operation of the lever to engage a reach of the 50 web inserted between the frame and lever.

2. A buckle comprising a sheet metal frame-member and lever-member, said frame member including a back having forwardly projected ears and a series of spaced apart teeth struck up from the back intermediate its upper and lower edges, extending rearwardly, and forming a series of openings in the back, said teeth adapted to grippingly engage the end of a web inserted beneath 55 said teeth at the outer side of the frame-member, portions of the web being exposed through said openings at the inner side of the frame, the lever-member being pivoted in the ears of the frame-member and including an operating arm and a clamping arm arranged at an angle thereto and having a series of teeth arranged in opposed relation to said series of openings in the back and adapted in the operation of the lever to 60 engage a reach of the web, inserted between the frame and lever, with the portions of the web exposed through said openings.

Signed at Bridgeport, in the county of Fairfield and State of Connecticut, this 13th 65 day of July, A. D. 1922.

MICHAEL HAWIE.
